ATTORNEY

UNITED STATES PATENT OFFICE.

HENRY H. TAYLOR, OF BRIDGEPORT, CONNECTICUT.

DESIGN FOR A SAFETY-PIN.

SPECIFICATION forming part of Design No. 31,303, dated August 1, 1899.

Application filed June 29, 1899. Serial No. 722,347. Term of patent 14 years.

To all whom it may concern:

Be it known that I, HENRY H. TAYLOR, a citizen of the United States, residing at Bridgeport, in the county of Fairfield and State of Connecticut, have invented and produced a new and original Design for a Safety-Pin; and I do hereby declare the following to be a full, clear, and exact description of the invention, such as will enable others skilled in the art to o which it appertains to make and use the same.

Referring to the accompanying drawings, Figure 1 is a side elevation of my newly-designed safety-pin. Figs. 2 and 3 are perspectives looking from the opposite ends of the pin when the latter is in open condition, and Figs. 4 and 5 are respectively top and bottom views of my newly-designed pin.

Similar numbers of reference denote like parts in the several figures of the drawings.

o The essential feature of my design consists of the intersecting loops at the closed end of the pin formed integral with the cross and pin bars, respectively.

1 is the usual lower or cross bar of the pin,

and 2 is the pointed pin-bar, these two bars 25 being so united at the closed end of the pin as to form intersecting loop portions 3 4. These loop portions when viewed from the top, the bottom, and the outside end present the appearance of two crossed wires, as shown at 30 Figs. 3, 4, and 5; but when viewed from the inside, looking toward said outside end, only a single deflected wire is seen which is common to the make-up of both of the coils, as shown at Fig. 2, which deflected portion I have 35 seen fit to particularly designate by the numeral 5.

Having thus described my invention, what I claim as new, and desire to secure by Letters Patent, is—

The design for a safety-pin as herein shown 40 and described.

In testimony whereof I affix my signature in presence of two witnesses.

HENRY H. TAYLOR.
